UNITED STATES PATENT OFFICE.

PETER GRABLER, OF ROCKY RIVER, OHIO.

COPYHOLDER APPARATUS.

Application filed June 21, 1924. Serial No. 721,414.

To all whom it may concern:

Be it known that I, PETER GRABLER, a citizen of the United States, residing in Rocky River, county of Cuyahoga, and 5 State of Ohio, have invented a new and useful Improvement in Copyholder Apparatus, of which the following is a specification.

My invention relates to apparatus for 10 holding copy in the form of loose sheets, or books or otherwise.

One of the objects of my invention is a simple, inexpensive, and light weight apparatus which does not tip over easily.

15 Another object is to provide such an apparatus with means for tilting the copy support plate thereof to any desired angle.

Another object is to provide such an apparatus with all necessary appliances for 20 conveniently and quickly placing copy onto the apparatus and removing it therefrom and to firmly hold this copy on the apparatus without any auxiliary appliance.

Another object is to provide such an apparatus with indicating means which is adjustable as to thickness of the copy as well 25 as to longitudinal positions on the copy.

Another object is to provide such an apparatus with adjustable friction means between the base and the upper structure to 30 permit this friction means to be adjusted periodically without any auxiliary appliances to permit this upper structure to be moved into desired positions at all times 35 without shifting the base thereof and to automatically retain these positions at all times.

Another object is to provide such an apparatus with adjustable friction means between the members of the indicating means to 40 permit this friction means to be adjusted periodically without any auxiliary appliances to permit the indicator bar to be moved longitudinally and radially without shifting the base or the support plate and to automatically retain this position at all times.

I am aware that copy holders have heretofore been made, but I am not aware that 45 such holders have been made with all of the necessary or convenient appliances incorporated therein as is done in the present invention. The copy holders heretofore made are either "top heavy" and tip over easily; are not provided with a simple and

efficient clip means to easily place any thickness of copy onto the support plate, and to easily remove it therefrom, and to firmly hold it thereon; they require repairs quite frequently as the parts become worn. 60

The present invention aims to provide a copy holder apparatus which overcomes the defects found in former holders, which has incorporated therein not only all appliances or conveniences necessary for the purposes of such an apparatus, but also the necessary means to take up wear without any auxiliary tools; thereby saving considerable time in the operation of the apparatus as well as eliminating practically all 70 repairs.

I attain these objects and these advantages by the mechanism illustrated in the accompanying drawing in which:

Fig. 1 is a front elevation of a copy 75 holder apparatus embodying the features of my invention.

Fig. 2 is a section, taken on a vertical plane indicated by the line 2—2 in Fig. 1, showing the structural details more clearly. 80

Fig. 3 is a section, taken on a horizontal plane indicated by the line 3—3 in Fig. 2, showing the relations between the support plate and the indicator means more clearly. 85

Fig. 4 is a section, taken on a horizontal plane indicated by the line 4—4 in Fig. 2, showing the hinge joints between the base and the support plate and between the support plate and the indicator means, and also the friction means of these joints more 90 clearly.

Fig. 5 is a section, on a larger scale, taken on a horizontal plane indicated by the line 5—5 in Fig. 2, showing the joint and friction means between members of the indicator means more clearly. 95

Fig. 6 is a section, on a larger scale, typical of the various joints of the apparatus, as on line 6—6 of Figs. 1 and 3 for 100 instance.

Similar reference characters refer to similar parts throughout the views.

The apparatus shown in the accompanying drawing comprises, principally, the base A, the copy support plate B, the copy clip C, the indicator bracket D, the indicator bar E, and the telescopic arm F. 105

The base A is made sufficiently heavy to provide a substantial support for the other parts of the apparatus and is, preferably, 110

formed substantially triangular to provide a good surface on the bottom thereof to prevent tipping over of the apparatus.

It is observed that the bottom of the base 5 A is provided with three annular rest pads 10, of rubber or otherwise, one at each apex of the triangular base, and that these pads project below the bottom of the main body of the base. This arrangement provides a 10 three point rest for the apparatus to permit the same to be set upon uneven surfaces and to rest securely under practically all conditions. This feature is important in an apparatus of the kind under contemplation. 15 The lug 11 projects upward from the top of the base A, above or opposite one of the pads 10, preferably with the longitudinal axis thereof inward of the longitudinal axis of this pad, to provide a good support 20 for the structure mounted on the base and to aid in preventing the apparatus from tipping over. In other words: the lug 11 is disposed on the top of the base, within the three pads located on the bottom of the 25 base, and closer to one of these pads than to the other two.

The copy support plate B is made of thin material to keep the same as light in weight as possible and is formed with the rib 12 30 to stiffen the same.

A pair of ears 13 and 14 are bent down from the lower end of the support plate B, on each side of the rib, and straddle the lug 11.

35 The bolt 15 passes through both of these ears and through the lug and forms a hinge pin to permit the plate B to swivel on the base A.

The head 16 of the bolt 15 rests against 40 the ear 13 and the wing nut 17, threaded to the bolt 15, bears against the ear 14.

Since the ears 13 and 14 are made of thin material they are flexible to some extent and can be manipulated by the nut 17 to increase or decrease the friction between 45 these ears and the lug. For instance, after this swivel joint wears and becomes too loose to retain the plate B in adjusted or desired position, the nut 17 may be tightened, thereby forcing the ears toward each other and against the sides of the lug 11; this tightening can be adjusted to a point where sufficient friction is created between the ears and the lug to retain the 50 plate B in adjusted position but permit the same to be swiveled on the bolt 15 without further manipulation of the nut 17 or without further auxiliary tools.

60 A pair of ears 18 and 19 are bent upward from the lower end of the plate B near the sides thereof.

The indicator bracket D has the ends thereof bent down to form the ears 20 and 65 21 disposed between the ears 18 and 19 respectively as clearly seen in Fig. 4.

The tubular rivets 22, shown on a larger scale in Fig. 6, may be employed on the bracket as a swivel or hinge pin. Such tubular rivet is light in weight, is easily installed, and is easily tightened either by the 70 heads thereof as is well known in the art or by expanding the same through the hole therein.

The indicator bar E is made very light 75 in weight and is provided with the handle 23 to conveniently permit of taking hold thereof for the purpose of manipulating the bar E to shift the same up or down to desired lines or positions on the copy or toward or away from the plate B to accommodate different thicknesses of copy.

The telescopic arm F, also very light in weight, is composed of the members 24 and 25. The outer end of the upper of the members 24 is hinged to the bar E while the outer end of the lower of the members 24 is provided with the pin 26 which is guided in the slot 27 provided in the bracket D for that purpose.

The outer end of the upper of the members 25 is provided with the pin 28 which is guided in the slot 29 provided in the bar E for that purpose, while the outer end of the lower of these members 25 is hinged to the bracket D.

The remaining ends of the members 24 are hinged to each other while the remaining ends of the members 25 are also hinged to each other.

The members 24 and 25 cross each other 100 and are hinged to each other at these crossings. The tubular rivet 22 is also employed at these hinge joints to provide light weight structure and adaptability for adjustment as previously set forth.

105 At the crossing of the middle members 24 and 25, the hinge joint is formed as shown on a larger scale in Fig. 5. This joint comprises the bolt 30 passing through both of the members, the washer 31 between the head of the bolt and the member 25, the washer 32 adjacent to the member 24, and the wing nut 33 threaded to the bolt 30 and bearing against the washer 32.

110 Upon manipulation of the wing nut 33, any desired frictional engagement between the members 24 and 25 may be attained to permit the arm F to be lengthened or shortened readily to permit the bar E to be moved up or down readily and to retain this bar in any desired position without any auxiliary instrument.

115 The guide feature of the arm F is provided to permit the bar E to be moved up or down; the free ends of the outer members 24 and 25 slide in and are guided in the slots 27 and 29 respectively for the purpose of always retaining the bar E in a horizontal position irrespective of what 120 vertical position it is moved into.

The copy clip C is mounted near the upper end of the support plate B and is journaled in the brackets 34 which are secured to the back of the plate B.

5 The clip C itself comprises the horizontal clip bar 35 disposed just inside of the upper edge of the plate B, the downwardly extending side members 36, and the journal members 37 substantially parallel with the 10 clip bar 35.

The bar 35 is disposed on the front of the plate B while the members 37 are journaled in the brackets 34 on the back of the plate B.

15 The coil springs 38 are disposed over the respective journal members 37, each having the end 39 thereof engaging one of the members 36 and the end 40 thereof resting against the back of the plate B. The 20 springs 38 are so wound and mounted that the tension thereof always tends to move the clip bar 35 toward the plate B to normally hold the copy thereon.

When it is desired to place a copy on the 25 plate B, the bar 35 is moved forward, away from the plate B, the copy is then placed on the plate and, upon releasing the bar 35, the springs 38 will rotate the clip C in its journal and force the bar 35 toward the 30 plate B and thereby hold the copy thereon.

It is observed that the clip bar 35 of the clip C lies across the plate B at the extreme upper edge thereof, that the members 36 are disposed some distance on each side of the plate B to permit the copy to extend therebetween, and that the members 37 are disposed on the back of the plate B so that they will not interfere with the copy.

By disposing the members of the clip C 40 as set forth, the indicator bar can move up to the top of the plate B and the copy G can readily hang over the upper edge of the plate as indicated in dotted lines in Fig. 2.

Modifications may be made within the 45 scope of the appended claims; therefore, without limiting myself to the precise construction and arrangements of elements shown and described,

I claim:—

50 1. A copy holder apparatus comprising, a base, a copy support plate mounted on said base and provided with a pair of ears projecting forwardly from this plate, an indicator means having a bracket mounted between said pair of ears and swivable thereon and in frictional engagement therewith to permit this bracket to be swiveled to desired positions and to remain in these desired positions.

60 2. A copy holder apparatus comprising, a base, a copy support plate mounted on said base and provided with two ears projecting

forwardly from this plate, an indicator means including a bracket having the ends thereof bent down to form ears disposed adjacent to respective ones of the first said ears, and a hinge pin through said adjacent ears to permit said bracket to be swiveled on said ears on the support plate and adapted to provide sufficient friction between said adjacent ears to permit said bracket to be swiveled to desired positions and to remain in these desired positions. 65

3. A copy holder apparatus comprising, a base, a copy support plate mounted on said base and provided with a pair of forwardly extending ears, a bracket swivable on said ears, a tubular rivet through each of the joints between said ears and said bracket to permit of easy adjustment of the friction of these joints, and an indicator means carried by said bracket. 70

4. A copy holder apparatus comprising, a base, a copy support plate mounted on said base and provided with a pair of forwardly extending ears, a bracket swivable on said ears, a telescopic arm having the lower end thereof operatively connected to said bracket, an indicator bar operatively connected to the upper end of said arm, tubular rivets 80 through certain of the joints of the members of said arm to permit of easy adjustment of the friction of these joints, and a screw with a wing nut through one of the joints of the members of said arm and thereby permit of manual adjustment of the friction between the members of the joint. 85

5. A copy holder apparatus comprising, a base, a copy support plate hinged to said base and provided with two forwardly extending ears, a bracket having two ears extending adjacent said ears on the copy support plate, one of each of said ears forming a pair, a copy indicator means carried by said bracket, a hinge pin through each of 90 said pairs of ears to permit said bracket to swivel on said ears of the plate to adjust said indicating means to different thicknesses of copy. 100

6. As an article of manufacture, a copy holder apparatus, comprising, a heavy base having an upwardly extending lug, a copy support plate made of thin and light weight material, a portion of the material of said plate bent backwardly to form a pair of ears straddling said lug, a hinge pin through said ears and said lug to form a hinge joint, another portion of the material of said plate bent forwardly to form a pair of ears, a line indicator mechanism hinged on the last 115 mentioned pair of ears, and a copy clip of wire journaled on the back of said plate. 120
